METAL CONTAINER

Karl Wilhelm Mauser, Waldeck, Germany

Application December 3, 1934, Serial No. 755,828
In Germany December 11, 1933

5 Claims. (Cl. 220—61)

In the metal containers as hitherto constructed with a ring-shaped seating for receiving the cover and its fastening means, the seating is fixed to the container wall in such a manner that it projects into the interior of the container. This has the disadvantage, that normally the container contents cannot be entirely removed. The residues remaining in the container can only be removed by an inconvenient manipulation.

10 It has already been attempted to arrange the ring-shaped seating so as to be flush with the interior of the container, by the container wall being drawn out in such a manner that it either embraces the ring-shaped seating from the outside or engaged in it from within. In the former case the construction was unsatisfactory, owing to the circumstance that the thin material forming the wall would not stand such a treatment and became torn. In the latter case it was found

15 that there was the disadvantage that there was no certainty of the sheet forming the wall bearing firmly in the ring-shaped seating and that the ring was still further loosened through external influences. On the closure means being stressed, the part of the ring-shaped seating which was formed from the material of the wall, yielded elastically, making it impossible to obtain a tight closure. A further great disadvantage in packing containers having a ring-shaped seating was, that for each of the usual kinds of closure adapted to the particular purpose a different ring-shaped seating had to be used. Those skilled in the art aim at making the metal packing containers suitable for a great variety of purposes, so that for one and the same container all the usual kinds of closures may be used.

20 The present invention provides a perfectly satisfactory solution of the problem and at the same time overcomes all the above disadvantages as regards the method of fixing the ring shaped seating.

25 The invention will now be more particularly described with reference to the accompanying drawing. Figs. 1 to 6 show constructional examples in which the ring-shaped seating *a* formed from flat or profiled strip metal is flush with the interior of the container. In Figs. 1 to 6 the connection between the ring-shaped seating *a* and the container wall *b* is effected by the part *c* which forms the extension of the lower abutment flange *e* being doubly beaded over with the container rim to form four layers of material. This double beading bears in Figs. 1, 2, 4, 5 and 6 closely against the lower abutment flange *e* of the ring-shaped seating *a*. Fig.

3 shows a constructional form of the ring-shaped seating, in which the double beading *b*, *c* bears closely against the container wall *b*, the abutment flange *e* covering the head of the double beading and thereby securing the beaded connection. In those cases in which the beaded connection is to be made fluid tight a packing *g* may be beaded in as well, as is shown in Fig. 2. In the described construction of the ring-shaped seating according to Figs. 1 to 6 the cover *d* is seated on the lower abutment *e* of the ring-shaped seating, which is unaffected by the beading operation.

5 A packing ring *r* of rubber or any other suitable material is placed between the cover *d* and 15 the seating *e*.

In Figs. 1, 4, 5 and 6 the ring-shaped seating is made of wedge-shaped strip, while Fig. 2 shows a ring-shaped seating made of uniformly flat strip. In the last named constructional form a relatively thin material which facilitates the beading operation may be used, a protective hoop *f* being provided for reinforcing the ring-shaped seating and for strengthening the container head. Such a protective hoop *f* is also shown in the constructional forms of Figs. 5 and 6. The ring-shaped seating according to Fig. 3 is of uniform thickness in that part which constitutes the abutment for the ring and the cover, while the beaded part is suitably thinner for facilitating the beading operation.

20 In the constructional forms shown in Figs. 1 to 3 the ring-shaped seating is of substantially rectangular cross-section and allows only of the employment of closures employing wedge-shaped rings and locking members.

25 Figs. 4—6 illustrate constructions of ring-shaped seatings having an approximately semicircular or ellipse-shaped cross-section. This form of ring-shaped seating enables all the usual kinds of closure to be used, such, for example, as closures employing wedge rings, tension rings and locking members, with one and the same ring-shaped seating. Thus Fig. 4 shows a wedge-shaped ring closure in which the wedge ring *m* acts as the closing means; Fig. 5 shows a locking closure with lock members *n* and finally Fig. 6 shows a tension ring closure in which the tension ring *o* forms the closing means. As is shown in Fig. 5, the cover *d* may be provided with a rim *p* extending over the ring-shaped seating *a*. This rim serves besides other purposes that of acting as a protection against the falling in of dirt which might get into the interior of the container, on the cover being opened. In the

constructional form shown in Fig. 6 it will be seen that the rim *p* of the cover also can act as an abutment for a second gasket.

This part of the invention satisfies an urgent requirement, the economic value of which is of the greatest importance. The manufacture of the metal containers is greatly simplified, owing to the circumstance that the separate manufacture of the parts of the ring-shaped seating required for the greatly differing closing means are replaced by a standard ring-shaped seating. It should also be borne in mind, that the ring-shaped seating of semicircular form can be made far more simply and cheaply than the parts of the ring-shaped seating hitherto used. The user is now put in the position of being able to use one and the same packing container for the most varied purposes which entail the employment of a variety of closing means. Finally the mode of fixing the ring-shaped seating according to the invention for the first time provides the possibility in practice of making in a rational manner containers with ring-shaped seating which is flush with the interior of the container, so that such containers can be completely emptied and satisfactorily cleaned.

What I claim is:—

1. A metal container having a cover, fastening means for the cover, and a ring-shaped seat-

ing for the cover and fastening means, which seating consists of strip metal and has a substantially U-shaped part for receiving the cover and fastening means, and a lower part, a prolongation of which is folded together with the edge of the container wall to form at least four layers of material at the joint, and which at its innermost part is flush with the interior of the container wall.

2. A metal container as claimed in claim 1, in which the prolongation of the lower part of the seating and the container wall are folded together so that the layers of material lie parallel to the lower limb of the U-shaped part.

3. A metal container as claimed in claim 1, in which the prolongation of the lower part of the seating and the container wall are folded together so that the layers of material lie parallel to the container wall.

4. A metal container as claimed in claim 1, in which the U-shaped part is of rounded shape.

5. A metal container as claimed in claim 1, in which the prolongation of the lower part of the seating and the container wall are folded together so that the layers of material lie parallel to the lower limb of the U-shaped part, and having a protective hoop fitting over the U-shaped part and the layers of folded material.

KARL WILHELM MAUSER.
